UNITED STATES PATENT OFFICE.

TOM B. WILLSON, OF PITTSBURGH, PENNSYLVANIA.

AUTOMATIC TELEPHONE APPARATUS.

Application filed June 5, 1925. Serial No. 35,129.

This invention relates to cleaning devices for dials of automatic telephones.

The objects of the invention are to provide an attachment for such telephones for the purpose of cleaning the figured portion of the dials thereof and of preventing dust from getting into the working mechanism thereof.

Referring to the drawings, Fig. 1 is a plan view of an automatic telephone dial mechanism, with the cleaning attachment of this invention indicated in connection therewith; Fig. 2 is a side elevation of the dialing mechanism and attachment; Fig. 3 is a side elevation of the cleaning attachment removed from the telephone; Fig. 4 is a plan view of the attachment removed; and Fig. 5 is a side view at right angles to that of Fig. 3, with portions of the cleaning attachment removed.

Referring to Fig. 2 an ordinary automatic telephone with a dialing mechanism thereon is illustrated. This comprises a telephone base 1, and the upright portion 2 leading to the mouthpiece, which being well understood is not illustrated. Mounted upon the base 1 is the housing 3 of the operating or dialing mechanism. This housing ordinarily has a white enameled face portion 4 upon which letters and figures used in operating the dialing mechanism are printed. The housing has an inner concentric raised portion 5, inside the figured dial face 4, and rotatably mounted outside and on this raised portion 5 is a perforated disk 6, having holes 7 exposing the several figures of the dial face 4, as indicated in Fig. 1. The disk 6 is mounted on the raised portion 5 by attachment to a central non-circular extension 8 attached to mechanism within the housing, and secured by a nut 9. The extension 8 passes freely through the disk 6, so that rotation of the disk 6 turns mechanism located inside the housing 3—5. A clearance space is provided by the telephone makers between the underside of disk 6 and the upper face of the housing 5, and it has been found that in this space dust and dirt rapidly accumulate. When exposed to usual conditions of industrial cities, and especially under unusual conditions such as dusty factories, this accumulation soon reaches the point where the mechanism becomes dirty, imposes wear on its parts and interferes with its operation. The operation of the dial,

which after each manipulation must be returned to zero position by a spring, becomes uncertain and is appreciably slowed up. Eventually the disk 6 must be removed and the dirt cleaned out to permit operation at all.

Means are provided to prevent the gathering of dust and dirt between the outer face of the housing 5 and the inner face of the disk 6, and also for preventing the gathering of dust on the dial face 4. This consists of a circular metal plate 20, having a centrally positioned non-circular opening 21, and a lateral radial extension 22, the edges 23 of the extension being turned down to form a retaining fork or groove for a resilient wiping member 24, as illustrated in Figs. 3 and 5. A resilient ring 25 is positioned on the inner face and around the outer portion of the disk 20, and attached to the disk by any suitable means.

This member 20 and its associated wiping member is incorporated in the dialing mechanism by removing the disk 6, positioning the disk 20 on the non-circular portion of the neck 8, and then replacing the disk 6 in operating position. The packing member 25 is of such thickness and of such resiliency as to just fill the space between the outer face of the housing 5 and the inner face of the disk 20 when positioned as shown in Fig. 2, without resulting in sufficient friction to slow up return of the disk after manipulation. This forms an effective means for preventing the collection of dust inside the ring, and protects the working parts of the dialing mechanism.

The wiping member 24 is of such size that its exposed face makes light contact with the enameled dial 4, and it is positioned as shown in Fig. 1, normally just under the finger-stop member 26, which limits forward movement of the dial in actual manipulation. Consequently by moving the perforation of the disk 6 that normally is over the portion of the dial marked "Operator", around clockwise into limiting position at the stop 26, the brush 24 will have passed entirely around the dial face 4, and have cleaned all dust therefrom. The normal use of such telephones will by this attachment keep the dial face clean and the rotating mechanism free from dust and dirt.

The members 24 and 25 are preferably of a soft felt, or similar material.

The advantages of this device, in preventing the gathering of dirt between the removable disk and dialing mechanism housing, which tends to slow up return of the dial to 5 normal position, and of continuously wiping off the lettered portions of the dial, will be readily apparent to those familiar with such structures.

I claim:

- 10 1. The combination with an automatic telephone dialing mechanism comprising a fixed dial face and a rotary manipulating disk, of a supplementary disk positioned between the dial face and the manipulating 15 disk mounted to rotate with the latter element, and a brush attached to the underside of the supplementary disk and adapted to make wiping contact with the dial face.
- 20 2. An attachment for automatic telephone dialing mechanisms comprising a stationary figured dial face and a rotatably mounted manipulating disk, the dial face having a central raised housing upon which said

manipulating disk is mounted, consisting of a supplementary disk adapted to be positioned between the housing and the manipulating disk and to rotate with the latter, a brush carried by the supplementary disk and adapted to make wiping contact with the dial face, and a resilient packing ring carried by the supplementary disk inside the brush and adapted to be positioned between the manipulating disk and the said housing.

3. In combination with the dialing mechanism of an automatic telephone comprising a dial face a raised central housing and a rotatable manipulating disk mounted on the housing and spaced therefrom, a supplementary disk positioned between the said housing and manipulating disk, and a packing 40 ring carried by the supplementary disk and positioned between the housing and manipulating disk.

In testimony whereof, I sign my name.

TOM B. WILLSON.
